BATTERY CLAMP

Application filed May 20, 1932. Serial No. 612,607.

This invention relates to clamps for battery terminals and has for an object to provide a clamp which may be put on or taken off without the aid of a tool, may be applied or removed in the dark, may be used where the battery is located in a limited space with only room enough to insert the hand through the space used for filling the battery with water, and when in use so firmly grips the battery terminal as to make tight electrical contact, while at the same time being so positively anchored in place as to be undisturbed by bumping, vibration, or other disturbances.

A further object is to provide a battery terminal clamp which will be quick opening and closing so that it may be applied or removed by simply inserting a finger underneath the operating lever to remove the device, closing of the operating-lever by pressure of a finger thereagainst serving to apply the device.

With the above and other objects in view the invention consists in certain novel details of construction and combinations of parts hereinafter fully described and claimed it being understood that various modifications may be resorted to within the scope of the appended claims without departing from the spirit or sacrificing any of the advantages of the invention.

In the accompanying drawing forming part of this specification,

Figure 1 is a side elevation of the battery terminal clamp in applied position,

Figure 2 is an enlarged cross section taken on the line 2—2 of Figure 1,

Figure 3 is a view similar to Figure 2 but showing the operating lever open to permit removal of the clamp, and,

Figure 4 is an enlarged longitudinal section through the clamp.

Referring now to the drawing in which like characters of reference designate similar parts in the various views, 10 designates a battery and 11 a battery post or terminal, which as usual, is somewhat frusto-conical in contour, as best shown in Figure 4.

The terminal clamp, comprising the subject matter of this invention, consists of a shell 12 which is substantially frusto-conical

in contour to snugly receive the post 11 and may be formed of any desired metal.

The shell is provided, in the bore thereof, with a slot 13 which is disposed parallel with the axis of the shell and also there is formed in the bore of the shell a slot 14 of less height than the slot 13 and which communicates therewith. The outer surface of the shell is cut away, as shown at 15 in Figure 3, to the depth of the slot 13 and one end 15 of the cut away portion is tapered to provide an end wall 16, while the opposite end is rounded to provide an end wall 17 opposite the wall 16.

A curved metal band 18 is seated in the slot 13 and one end of the band is provided with a hook 19 which engages over the oblique end wall 16, while the opposite end of the band is provided with an eye 20. The hook anchors the band in place while the eye forms means for attaching the operating lever mechanism to the band for expanding or contracting the band, which preferably, is formed of spring metal.

A plurality of metal plates 21 are fixed at spaced intervals upon the inner face of the band, these plates being of sufficient height to be loosely received in the slot 14. Each plate is equipped with a spur 22 which penetrates the battery post 11 when the band is contracted. The plates 21 are arcuate and also are tapered on the inner face whereby they may conform snugly to the frusto-conical contour of the battery post 11.

For expanding and contracting the band 18 an arcuate operating lever 23, formed of spring metal, is provided with an eye 24 at one end to receive a pivot pin 25 which is mounted vertically in the cut away portion 15 of the shell. The opposite end of the lever is struck upwardly to provide a raised tip 26 underneath which the finger may be inserted to rock the lever open. A link 27, formed of spring metal, is provided with an opening 28 at one end to receive the eye 20 of the band 18, as shown in Figures 1 and 3. At the opposite end, the link is provided with spaced hinge ears 29, as shown in Figure 1, through which, and a hinge ear 30 on the lever 23, a pintle 31 is passed. Both the link

and the lever are arcuate in outline to snugly conform to the contour of the shell.

It will be seen by referring to Figure 2 that when the lever 23 is rocked closed against the shell the link 27 contracts the band 18 radially so that the spurs 22 of the plates 21 are embedded in the surface of the battery post 11. Thus a good metal to metal contact is produced so that a positive electrical connection is made between the shell and the battery post. Since the spurs penetrate the post, jars and shocks will not dislodge the device from the post. To remove the device from the post, it is simply necessary to insert the finger underneath the raised tip 26 of the lever and rock the lever 23 to the open position shown in Figure 3. The link 27 expands the band 18 radially in the slot 13 and withdraws the plates 21 into the slot 14 so that the spurs are retrieved from the battery post whereupon the shell may be readily slipped off the post. This operation may be performed in the dark or in restricted spaces without the use of tools.

The shell is equipped with a top boss 32 to receive the battery cable 33, as shown in Figures 1 and 4.

From the above description it is thought that the construction and operation of the invention will be fully understood without further explanation.

What is claimed is:

1. A battery clamp comprising a shell adapted to receive a battery terminal post, said shell having a slot formed in the bore thereof and opening through the outer face of the shell at one side of the shell, a metal band in the slot having one end anchored stationary, an arcuate lever pivoted in the side opening, an arcuate link pivoted to the lever and to the free end of the band, actuation of said lever to closed position against the outer face of the shell moving the link to contract the band radially in the groove, and projections integral with the band and adapted to engage the battery post and be held snugly thereagainst when said band is contracted.

2. A battery clamp comprising a shell having a bore adapted to snugly receive a battery post, there being an arcuate slot formed in the inner wall of the bore, there being a second slot formed in the shell concentric with the axis of the shell and disposed at the end of the first named slot, the first named slot being of less height than the second named slot, both of said slots opening through the outer face of the shell at a lateral point on the shell, an arcuate band of metal fitting in the second named slot, spaced metal plates carried by the band fitting in the first named slot and provided with spurs adapted to penetrate a battery terminal post when said band is contracted to move said plates into contact with the wall of the post,

means for anchoring one end of the band stationary, and a lever mechanism pivoted in said opening at said lateral point in the wall of the shell and operably engaged with the free end of the band to contract and expand the band.

3. A battery clamp comprising a shell having a substantially frusto-conical bore, an arcuate slot on the wall of the bore opening through the outer face of the shell at a lateral point in the shell, one wall of said opening being beveled and the opposite wall being rounded, an arcuate metal band seated in said slot and having a hook at one end engaging said tapered wall to anchor the band at said end to the shell, an arcuate operating lever pivoted in said opening at said lateral point, a link pivotally connected to the lever and to the free end of the band adjacent to said rounded wall, rocking of said lever moving said link to expand or to contract said band radially in said slot, and a metal spur operatively connected to the band and penetrating the battery post when said band is contracted by movement of the lever to closed position.

In testimony whereof I affix my signature.

GEORGE L. MITCHELL.
